UNITED STATES PATENT OFFICE.

HENRY A. BILLINGS, OF PROVIDENCE, RHODE ISLAND.

POWER MOLDING-MACHINE.

Specification forming part of Letters Patent No. 33,291, dated September 17, 1861.

To all whom it may concern:

Be it known that I, HENRY A. BILLINGS, of the city and county of Providence, and State of Rhode Island, have invented a new and useful Improvement in Power Molding-Machines; and I do hereby declare that the following specification, taken in connection with the drawings making a part of the same, is a full, clear, and exact description thereof.

Figure 1 is a perspective view. Fig. 2 is a view of one-half of a molding-flask, showing the molding-board with a pattern placed upon it. Fig. 3 is a cross-section of the same.

The invention which is the subject of this patent is designed to facilitate the exercise of that part of the molder's trade which is called "match-plate work," by accomplishing, through the aid of mechanical agents, a majority of the labor which has been usually performed by hand. This branch of the trade has been ordinarily exercised in the following way: The pattern is placed by the molder within the molding-flask, upon what is called the "molding-board," or the board which serves for the bottom of the flask. The sand is then heaped upon the pattern, rammed down with a wooden instrument, called a "rammer," even with the top of the sides of the flask, and then the flask is turned with its bottom side up. The board which served to support the pattern and the sand is then lifted up, when the patterns are disclosed embedded in the sand. The molder then removes the pattern from the sand, leaving thereby a matrix to be filled with the metal. Two flasks, in each of which is an impression of a half-pattern, are then placed together, so that the impression in each exactly corresponds, and the mold is, with the exception of some further preparation not necessary to be described, ready to be filled.

My invention is as follows: In the accompanying drawings, A A represents the frame of the machine. An endless traveler, B B, extends the whole length of the machine and passes around suitable rollers or chain-gears, U U', so that when motion is given to the shaft J the pulleys L and M, attached to the shaft of the chain-gear, will be put in motion also. A flask, Fig. 2, constructed with flaring sides, as shown in the cross-section, Fig. 3, having the patterns arranged in position

upon the molding-board, is now placed upon the traveler at the front of the machine. Upon the frame-work K K is mounted the rocker N, the arms of which support the sieve C V. Molding-sand having been supplied to the sieve the belt a a gives motion to the shaft R, which, through the connecting-rod Q, one end of which is pivoted to the crank-plate P at the extremity of the shaft R and the other end to an arm on the rocker-shaft, oscillates the sieve. The flask, Fig. 2, as it is carried by the traveler under the sieve C, is filled with sand, and is conveyed toward the other end of the machine. In its progress it encounters the fluted roller D, which is made to revolve from left to right by the toothed gear I working into the teeth of the pinion H on the end of the roller at a higher speed than that of the traveler. The fluted edges of this roller bury themselves in the sand in the flask and crush it against the sides and bottom of the flask, at the same time throwing off the surplus sand in advance of the flask. The flask next passes under the cylindrical roller E, which, as it derives its motion from the same source as the fluted roller D, revolves in the same direction. By this roller the sand in the flask is laid smooth and thoroughly compressed. The flask is now delivered at the rear of the machine and is removed by an attendant, after which the patterns are withdrawn and the matrix prepared to receive the metal in the usual way by hand-labor.

It is evident that any number of flasks can be successively passed through the machine, each one in turn being subjected to the several operations described.

In order that the traveler B B shall resist the pressure of the rollers D and E, I place an unyielding frame-work or table underneath the rollers, and mortised or otherwise firmly secured to the frame A A of the machine, against which the traveler is sustained while the sand is being crushed in the flask. The journals of the rollers D and E are mounted in boxes T T, which are capable of sliding up and down between the guides F F F, and are adjusted to any desired position by the screw-rods c c.

Instead of two compressing-cylinders, as shown in the drawings, one single cylinder may be with good advantage employed, in

which case it should have a cylindrical surface. I prefer, however, to use two cylinders, the surface of one of which is fluted, as described, though the use of one only, arranged in the combination shown by me, would be within the principle of my invention.

What I claim as my invention, and desire to secure by Letters Patent, is—

The combination of the endless traveler B, the sieve C V, or its equivalent, with one

or more compressing-cylinders, D or E, such combination operating substantially as described, for the purposes specified.

In witness whereof I have hereunto set my hand.

HENRY A. BILLINGS.
